DESIGN FOR A SANDAL OR SIMILAR ARTICLE

Jacob Stein, New York, N. Y.

Application November 3, 1936, Serial No. 65,663

Term of patent 14 years

To all whom it may concern:

Be it known that I, Jacob Stein, a citizen of the United States, residing in the city, county, and State of New York, have invented a new, original, and ornamental Design for a Sandal or Similar Article, of which the following is a specification, reference being had to the accompanying drawing forming a part thereof.

The figure is a perspective view of a sandal or similar article, showing my new design. Both sides of the upper are identical. Likewise, the ankle closure has the same appearance throughout, save where the ribbons are tied into bows.

An essential feature of the sandal is the particular pattern and arrangement of the perforations. Said upper has an ankle closure which is provided with horizontal and separated perforations. Said ankle closure has separate ends.

Ribbons are laced through the perforations of the ankle closures and said ribbons have their ends tied into bows.

I claim:

The ornamental design for a sandal or similar article, substantially as shown and described.

JACOB STEIN.
